UNITED STATES PATENT OFFICE.

JOHN R. EMMERT, OF CHICAGO, ILLINOIS, ASSIGNOR TO EMIL J. PAIDAR CO., A CORPORATION OF ILLINOIS.

RECLINING CHAIR.

Application filed August 28, 1926. Serial No. 132,102.

This invention relates to a reclining chair primarily adapted for use in beauty parlors and the like.

It is an object of this invention to provide a simplified structure which may be operated from either side and in which the leg rest, the foot rest, the seat and the back may be simultaneously swung into alignment.

The invention comprises the novel structure in combination with parts hereinafter described and more particularly pointed out and defined in the appended claim.

In the accompanying drawings which illustrate a preferred embodiment of this invention and in which similar reference numerals refer to similar features in the different views:

Figure 1 is an elevational view of a reclining chair involving this invention showing, in dotted lines, the positions of the different parts when swung into alignment.

Figure 2 is a sectional view with parts in elevation taken substantially upon the line II—II of Figure 1.

Figure 3 is an enlarged sectional view with parts in elevation, taken substantially upon the line III—III of Figure 2.

Figure 4 is an enlarged sectional view taken substantially upon the line IV—IV of Figure 3.

Figure 5 is an enlarged sectional view taken substantially upon the line V—V of Figure 3.

As an exemplification of this invention there is shown a chair having four legs 1 which are supported upon castors 2. These legs are connected together by longitudinally extending braces 3, and rear and front transversely extending braces 4. A U-shaped bearing 5 is supported between the longitudinally extending member 3. A pair of spaced standards 6 rise from the bottom of the U-shaped member, and a pair of clutch members 7 and 8 are positioned between the standards 6. A bolt 9 is adjustably threaded through one standard for engaging with the clutch member 8, to take up wear, and a shaft 10 which is journalled in the end wall of the U-shaped bearing member is threaded through the other standard 6 and engages the other clutch member 7. An arm 11 is rigidly secured upon the shaft 10 and a spring 12 is positioned between the arm 11 and the opposed standard 6. One end of the spring is preferably anchored to the standard 6, while the other end thereof is anchored to the arm 11.

Directly above the shaft 10 there is journalled in the lateral arm of the bearing 5 a second shaft 13 upon which a dog 14 is rigidly secured. The dog 14 is mounted in the plane of the arm 11 and is adapted for engaging and swinging the same, as will hereinafter be more fully explained. The interior side of one of the lateral arms of the bearing 5 is provided with an arcuate lug 15 and a collar 16 is rigidly secured to the shaft 13 adjacent said lateral arm. The collar 16 is provided with a peripheral cut-out portion or recess 17 forming opposed shoulders which are adapted for engaging the shoulders 15^a formed by the lug 15 for limiting the oscillation of the shaft 13 and the handles 18 thereof. Each end of the shaft 13 is provided with an up-standing handle portion 18 whereby the shaft 13 may be swung from either side of the chair.

Upon the upper end of each leg there is pivoted a bracket 19. Each bracket is pivoted intermediate its ends, as indicated at 20, so that the same can swing with respect to its supporting leg. The lower ends of these brackets are pivoted to cradle members 21 that support the seat 22. It will be understood that the parts shown on one side of Figure 1 are duplicated upon the opposite side thereof. To the upper ends of the brackets 19 are respectively pivoted the brackets 23 which support the side arm 24 of the chair.

The aforementioned brackets 19 at the two rear posts are provided with integral rearwardly extending attaching members 25 to which the back of the chair 26 is secured, whereby the same is caused to swing with the brackets 19. The front brackets 19 extend downwardly and below the connection with the cradle 21, are forwardly offset to a slight degree for supporting the leg rest 27 to the lower end of which a foot rest 28 is pivoted. A rod 29 is secured to the leg rest 27 and extends between the aforementioned clutch members 7 and 8.

In the operation of this chair, the lever 18 upon either side of the chair is swung for rocking the shaft 13 causing the dog 14 to actuate the arm 11 for rocking the shaft 10 which on account of its screw threaded connection in the bearing standard 6 will unscrew and release the clutch member 7 from frictionally binding the rod 29. When the rod 29 is thuswise released, the back 26 may be reclined, as shown in dotted lines, and the

leg rest elevated, as shown in dotted lines. During this operation the seat 22 will be elevated and shifted forwardly. The parts may be restored by a reverse operation. It will be noted that in the oscillation of the levers 18, the rocking of the shaft is limited by the engagement of the ends of the recess 17 with the shoulders 15^a whereby the handles are prevented from falling and the throw of the cam 14 is limited. In other words, the oscillation of the shaft 13 is limited to an arcuate defined by the distance between the shoulders 15^a. This provides a more rigid and solid construction than structures heretofore used.

I am aware that many changes may be made, and numerous details of construction may be varied through a wide range without departing from the principles of this invention and I, therefore, do not purpose limiting the patent granted hereon, otherwise than necessitated by the prior art.

I claim as my invention:

In a reclining chair having a rod controlling reclining movements thereof, a U-shaped bearing member, an operating shaft journaled through the upright of said bearing member and having handles at its opposite ends, an arm on said shaft, a collar on the shaft adjacent to one of said uprights, said collar and said upright having coacting means to limit relative movement of the shaft, a pair of spaced-apart standards rising centrally of said bearing member, clutch blocks between said standards normally engaging said controlling rod, a second shaft controlling said clutch and journaled in one of said uprights and one of said standards, a spring for moving said shaft in one direction to tighten the clutch blocks, and a dog on said second shaft and engaging the said arm of the operating shaft.

In testimony whereof I have hereunto subscribed my name.

JOHN R. EMMERT.
